UNITED STATES PATENT OFFICE.

ADAM K. BOWMAN, OF GREENSBURG, PENNSYLVANIA.

SHOW-CASE.

SPECIFICATION forming part of Letters Patent No. 310,024, dated December 30, 1884.

Application filed September 20, 1883. (Model.)

To all whom it may concern:

Be it known that I, ADAM K. BOWMAN, of Greensburg, in the county of Westmoreland and State of Pennsylvania, have invented certain new and useful Improvements in Show-Cases with Brackets for Holding Yarn, of which the following is a full, clear, and exact description.

The object of this invention is to provide a show-case in which assorted yarns and other goods may be stored and exposed for sale.

It consists in an upright case with glass doors, and having removable partitions and brackets, as will be hereinafter more fully described.

Reference is to be had to the accompanying drawings, forming part of this specification, in which similar letters of reference indicate corresponding parts in all the figures.

Figure 1 is a front elevation. Fig. 2 is a sectional plan view of a show-case arranged with the brackets for holding assorted yarns. Fig. 3 is a perspective view of part of one of the posts by which the brackets are supported. Fig. 4 is a perspective view of a bracket-support for yarn.

The show-case A is upright in form, made with doors a on two opposite sides of the case, and divided into compartments by removable partitions a³, which fit into grooves a⁶ in the top and bottom of the case A.

Through the center of case A are vertical posts B, reaching from top to bottom, and secured by entering a mortise at the bottom a', and at the top by screws passing through the top a' and entering the top b' of the post B. Posts B are grooved on the sides which face the doors a, and have on the same faces, on each side of the groove, a plate of metal, b, firmly secured thereto and overlapping the edge of the groove, and thus forming the recess b', adapted for the reception of guide c of the bracket C. The shelf d of the bracket is a thin strip of metal or board, having at one end the guide c, which guide is adapted in width to pass between the metal plates b. Plates b do not reach quite to the top of post B, a space, b³, being left sufficient for the insertion of the arms c' of guide c. Guide c has arms c', adapted in their length from end to end to fill the width of recess b' in rear of plates b, and to impinge against the rear face of plates

b. The shelves d have on their under side staples d', adapted to receive the arms c' of the guides c and to secure them thereto. The 55 arms c' of the guides are provided with shoulders c' c', which impinge against the front face of the plates b. The brackets C are usually supported on the yarn D beneath them; but if they are raised a little, the 60 front edge of the shelf d will drop a short distance, in which position it will be locked by the guides to the plates b by the impingement of the arms c' against the rear 65 face of plates b, and the impingement of shoulders c' of the arms c' against the front face of plates b. The brackets C are formed by passing the outwardly-extending arms c' of the guide c through the staples on the under side of the shelves d. The bracket is then placed 70 in the recess b', through the space b' at the top of the post B, the arms c' of guide c passing in the rear of the plate b, the shelf being held slightly raised from the horizontal position. The bracket can then be moved downward to any desired position, in which position it will be held when it is released by the impingement of the arms c' and shoulders c' 75 against the plates b b. Other brackets can be placed in like manner, and they are stored 80 with yarn D, each bracket receiving only one color or shade. The shelves are numbered, and the yarn is sold by samples corresponding in number and color with the yarn on the several shelves. The yarn is removed hank 85 by hank as sold, and the upper shelves being supported by and resting upon the yarn D on the shelves below, they settle down as the yarn below them is removed. When sufficient space is thus made another bracket is inserted. 90

The advantages of my invention are that assorted yarns may be kept for retail sale in separate compartments of the case without being mixed or disarranged, and more yarns may be placed in other separate compartments as soon as room is made for them without disarranging those already in the case. 95

Having thus described my invention, I claim as new and desire to secure by Letters Patent—

1. An improved show-case, provided with 100 movable partitions and adjustable brackets held in vertical posts between said partitions, substantially as herein shown and described.

2. The show-case A, for exhibiting yarn,

provided with the removable partitions a^3 , and the bracket C, carrying shelves d , and held adjustably in vertical grooved posts B, substantially as herein shown and described.

5 3. In a show-case, the combination, with vertical posts B, provided with grooves having plates extending over the edges of the same, of the brackets C, having guide c, provided with arms c' , substantially as herein shown and described.

10 4. In a show-case, the combination, with

the vertical grooved post B, provided with the plates b, overlapping the edges of the grooves, of the bracket C, provided with the guide c, having arms c' , and the arm c^3 , having shoulders c^2 , and the shelf d, secured on the said arm c^3 , substantially as herein shown and described. 15
